UNITED STATES PATENT OFFICE

159,063

TOY BIRD

Clifford E. Harsh, Glendive, Mont.

Application June 9, 1949, Serial No. 3,163

Term of patent 3½ years

(Cl. D34—2)

To all whom it may concern:

Be it known that I, Clifford E. Harsh, a citizen of the United States, residing at Glendive, in the county of Dawson and State of Montana, have invented a new, original, and ornamental Design for a Toy Bird, of which the following is a specification, reference being had to the accompanying drawing, forming part thereof.

Figure 1 is a front perspective view of a toy bird, showing my new design, and

Figure 2 is a rear perspective view of the same.

I claim:

The ornamental design for a toy bird, as shown.

CLIFFORD E. HARSH.
